UNITED STATES PATENT OFFICE.

JOSEPH K. RUSH, OF SYRACUSE, NEW YORK.

SHORT-CIRCUIT DETECTOR.

1,115,580.

Specification of Letters Patent.

Patented Nov. 3, 1914.

Application filed November 18, 1910, Serial No. 593,092. Renewed March 26, 1914. Serial No. 827,493.

To all whom it may concern:

Be it known that I, JOSEPH K. RUSH, of Syracuse, in the county of Onondaga, in the State of New York, have invented new and useful Improvements in Short-Circuit Detectors, of which the following, taken in connection with the accompanying drawings, is a full, clear, and exact description.

This invention relates to certain improvements in short circuit detectors for electrical distributing systems such as gas lighting, call bell and other circuits in which a greater or less number of translating devices or circuit closers are connected.

The primary object is to cause the automatic operation of a single signal by the short-circuiting of any one or more of a series of circuits in which such translating devices or circuit closers are connected.

Another object is to provide a simple and compact device whereby any line or connection in which the short circuit exists may be easily and quickly located from a single testing point or station so that the trouble may be remedied without seriously disturbing any of the other lines or connections.

A further object is to enable any one of a series of electric gas lighters with which a hotel or other building may be equipped to be used to operate a call signal or annunciator at the main office or other central station whereby the occupant of any room in which such gas lighter is located may get the desired service without the use of a separate call system.

Other objects and uses relating to specific parts of the device will be brought out in the following description.

In the drawings Figure 1 is a diagrammatic view of my invention as connected to a plurality of gas lighting and call circuits with the corresponding circuit closers there-
in. Figs. 2 and 3 are respectively front and side elevations of the detached signal and line testing device. Figs. 4 and 5 are transverse sectional views taken respectively on lines 4—4 and 5—5 Fig. 1.

The central testing station constituting one of the main features of my invention comprises a plurality of terminal connections or connectors —1— which are systematically grouped in compact space upon and electrically connected to a common feed conductor —2— and are each adapted

to be connected in one side of one of a corresponding number of circuits in which the gas lighters, circuit closers or other translating devices are connected. These terminal connections or connectors —1— may be of any suitable commercial type capable of normally closing these portions of the circuits and at the same time permitting any one or more of such circuits to be quickly and easily broken and reclosed at will in making the tests for any existing short circuit and for this purpose I have shown the well known form of spring clamp in which the adjacent ends of the corresponding line wires are frictionally held.

The feed conductor —2— preferably consists of a flat metal plate to which the terminal connections —1— are directly secured by rivets or other fastening means, said plate also serving as a support for a suitable signal as an electric bell —3— and insulation —4— by which said bell is insulated from the plate.

By mounting the signal —3— and terminal connections —1— upon the same plate in the manner described I am enabled to produce a neat and compact testing device as a complete article of manufacture capable of being easily and quickly installed within a very small space in any part of a building where such a device might be useful and most easily accessible.

Current may be supplied to the several line circuits and to the electric signal from any suitable source of electric energy as a battery —4— and when the device is used in connection with one or more gas lighting circuits one pole of the battery is connected by a wire —5— to one terminal of a spark coil —6— having its other terminal connected by a wire —7— to the plate —2— through the medium of a terminal connection —1'— similar to those previously described.

In order that this testing and signal device may be clearly understood I have illustrated somewhat diagrammatically in Fig. 1 two different forms of gas lighters —8— and —9— and also two different forms of circuit closers —10— and —11—, each of the lighting devices and circuit closers being connected in a separate circuit having one side thereof connected to the corresponding terminal connection or circuit breaker —1— on the plate —2— which is in electrical connection with one pole of the battery

while the other side of each circuit is electrically connected to the opposite pole of said battery. For example, the electric gas lighting device —8— is associated with an ordinary gas tip —a— and consists of suitable terminals, one of which is movable into and out of contact with the other terminal to produce a spark in the path of the escaping gas when the latter is turned on but may be operated merely as a circuit closer without turning on the gas for a purpose hereinafter described, one of the terminals of this gas lighter or circuit closer being connected by a wire —12— to one of the terminal connections —1— while the other terminal is connected by a wire —13— to a return conductor —14— leading to the battery —4—.

By turning on the gas in the usual manner and then operating the electric gas lighter —8— by means of a pull cord —15— or other suitable operating device, the circuit will be closed through the coil —6— thereby producing a spark at the tip of a gas jet —a— and igniting the gas, the current passing from the battery —4— through the conductor —5— and coil —6— and thence through the conductors —7—, —2— and —12— to the gas lighter and return through the conductor —14— to the battery.

When the coil —6— is employed for gas lighting the signal —3— is preferably connected by conductors —16— and —17— to the opposite terminals of the coil and therefore a part of the current passes through the conductors —16— and —17— sufficient to operate the signal —3—, so that any number of these circuit closers —8— located in different rooms or different parts of a building may be operated independently of their functions as gas lighters to close their respective circuits through the signal —3— and thereby serve as an independent call system for any service or purpose for which such a call system might be used, thereby obviating the necessity for an extra call system.

When no spark is required in any of the circuits and the device is used simply as a signal system for calls, burglar alarms and similar uses, the spark coil —6— may be omitted under which conditions the conductor —16— would be connected directly to the wire —5— or adjacent pole of the battery while the conductor —17— would be connected directly to the wire —7— or conductor —2— so that to close any one of the circuits as, for example, that in which the circuit closer —8— is connected would cause the current to pass from the battery —5— through the conductor —16— to the signal —3— and thence through the conductors —17—, —7—, —2— and —12— to the circuit closer —8— and return through the conductor —14— to the battery.

One side of the circuit closer —10— is connected by a conductor —18— to one of the connectors —1— and its other side is connected by a conductor —19— to the return conductor —14— leading to the battery —4— for closing the circuit and operating the signal —3— for calls, burglar alarms, and other uses to which it might be applied and it is evident that any number of these circuit closers may be used throughout a building and connected to the same or different circuit breakers —1— as for example an additional switch —10'— which is connected in parallel with the circuit closer —10— Fig. 1.

The automatic gas burner —9— is also of the usual commercial type in which the gas is turned on and ignited and turned off by suitable electrically operated means controlled by the double switch or key —11— which is connected by a conductor —20— to one of the connectors —1— and is also connected by separate conductors —21— and —22— to the automatic gas lighter —10—, the latter being connected by a conductor —23— to the return conductor —14— so that by pressing the light button at the top of the key —11— the circuit will be closed through the line —21— and gas lighter —11— to turn on and ignite the gas and by pressing the dark button at the bottom of the key the circuit will be closed through the line —22— and burner to shut off the gas and open the igniting circuit.

It is now clear that the signal —3— may be operated at will by either of the circuit closers —8—, —10—, —10'— or —11— and that such signal will continue to operate as long as either of the switches are closed so that in case any one of the switches should remain in its closed position or in case there should be a short circuit in any one of the line wires, as for example, at —a— the particular line in which the closed switch is connected or that in which the short circuit exists may be readily located by successively opening and closing the connectors —1— until the signals cease to operate, thereby indicating that the short circuit or closed switch exists in the line which is connected to that particular connector and enables the operator to readily trace and remedy the trouble without disturbing any of the other lines.

If there should be no attendant present capable of making this test and the bell should continue to ring the entire testing device and other parts of the system may be entirely cut out of the battery circuit by simply disconnecting the line wire —7— from its conductor —1'— to save the battery from running down or exhausting its energy.

What I claim is:

The combination with a central station provided with a plurality of slip terminals;

a common feed conductor for said terminals, a sparking coil having one terminal connected to said feed conductor, a battery having one pole connected to the other terminal of the sparking coil, a bell connected to the terminals of said sparking coil, a plurality of circuit closers connected to said terminals, and a wire connecting the remaining pole of said battery with said circuit closers. In witness whereof I have hereunto set **10** my hand on this fifth day of November, 1910.

JOSEPH K. RUSH.
